UNITED STATES PATENT OFFICE.

CLARENCE A. MUSSELMAN, OF PHILADELPHIA, PENNSYLVANIA.

DESIGN FOR A BOOK-COVER.

No. 39,814.

Specification for Design.

Patented Feb. 9, 1909.

Application filed November 21, 1908. Serial No. 463,927. Term of patent 3½ years.

To all whom it may concern:

Be it known that I, CLARENCE A. MUSSELMAN, a citizen of the United States, residing in the city and county of Philadelphia, State of Pennsylvania, have invented a new, original, and ornamental Design for Book-Covers, of which the following is a specification, reference being had to the accompanying drawing, forming part thereof.

The figure is a view of a book cover showing my novel design.

I claim:—

The ornamental design for a book cover, as shown.

CLARENCE A. MUSSELMAN.
